UNITED STATES PATENT OFFICE.

WILLIAM AUSTIN ESTES, OF VASSALBOROUGH, MAINE, ASSIGNOR OF ONE-HALF TO FREDERICK WILLIAM WATSON, OF TORONTO, CANADA.

APPARATUS FOR TRANSPLANTING TREES.

SPECIFICATION forming part of Letters Patent No. 423,746, dated March 18, 1890.

Application filed October 1, 1889. Serial No. 325,638. (No model.) Patented in Canada May 1, 1889, No. 31,223.

To all whom it may concern:

Be it known that I, WILLIAM AUSTIN ESTES, of Vassalborough, in the county of Kennebec, and in the State of Maine, have invented 5 certain new and useful Improvements in Apparatus for Transplanting Trees, (for which I have obtained a patent in the Dominion of Canada, No. 31,223, bearing date of May 1, 1889;) and I do hereby declare that the following is a full, clear, and exact description thereof, reference being had to accompanying drawings, in which—

Figure 1 is a perspective view of my wagon as used for the transportation of a tree. Fig. 15 2 is a plan view of the same. Fig. 3 is a side elevation of said wagon. Fig. 4 is an enlarged elevation of the rear end of said wagon; and Fig. 5 is an enlarged side elevation, partly in section, of the spring-bolster.

20 Letters of like name and kind refer to like parts in each of the figures.

The object of my invention is to facilitate the transplantation of trees and to enable them to be easily and safely transported; to 25 which end my said invention consists, principally, in the means employed for supporting the trunk of a tree, substantially as and for the purpose hereinafter specified.

It consists, further, in the means employed 30 for supporting the roots of a tree, substantially as and for the purpose hereinafter shown.

It consists, further, in the means employed 35 for connecting and relatively adjusting the trunk and roots supporting parts of my apparatus, substantially as and for the purpose hereinafter set forth.

It consists, finally, in the combination of 40 the rear and front axles with their connecting parts, substantially as and for the purpose hereinafter shown and described.

In the carrying of my invention into practice I employ an axle A, which has the usual straight form, and upon its upper side is provided with an extension A', that substantially doubles its vertical dimensions. Said extension may be formed with said axle, or may be constructed separately and afterward attached thereto, as desired. Upon each end 45 of said axle is journaled a ground-wheel B,

which furnishes a rolling support therefor. Upon the front and rear sides each of the axle A are secured two strips a and a', which are arranged vertically and in parallel lines, and between each pair of the same is placed 55 a strip C, that corresponds in width to the space and has preferably a length equal to about twice the combined width of said axle and its upward extension. Said strips are connected at their lower ends by means of a 60 block c, that extends between and is attached to the same, while at their upper ends said strips are connected by means of a second block c', which fills the space between the same and has each of its ends projecting beyond the edges thereof, as shown. The strips C and C', thus connected, form a bolster which is adjustable vertically upon or with relation to the axle A, and when so adjusted may be secured in place by means of pins D and D', 70 that are inserted within coinciding holes c² and c'² and a' and a', which are formed, respectively, in said bolster and axle. Several of said holes c² and c'² are provided in said bolster, so as to permit of its adjustment to various heights. In order that such adjustment may be readily effected, the weight of said bolster is supported by means of two springs E and E', one of which is placed between each projecting end of the block c' and the upper 75 side of the axle-extension A'. To the upper end of said bolster is secured a plate or tree-saddle F, that transversely has a concave upper side, is arranged at a right angle to the line of the axle, has about one-fourth of its 80 length in front of said axle, and has a rearward and an upward inclination, as shown. A bracket E', placed between the rear side of said bolster E and the under side of the rear portion of said saddle F, strengthens the 85 connection between said parts and furnishes an additional support for the latter.

With the axle A and its connecting parts I employ another or front axle G, which has journaled upon each of its ends a ground-wheel H and has connected with its front side a pole I, that is provided with the usual means for attaching thereto a span of draft-animals.

To the rear side of the axle G is connected in any usual manner a platform K, which has 90 95 100

the form shown in Fig. 2 and within its rear wide portion is provided with four rollers *k* and *k*, that are journaled upon horizontal axles, which are arranged at a right angle to the line of draft. Said platform is connected with the rear axle *A* by means of two chains *L* and *L*, one of which extends from each side of the former upward and around a roller or windlass-spool *M*, that is journaled upon the lower side of said axle, is adapted to be turned by means of a bar, and upon one end is provided with a ratchet-wheel *m*, which is engaged by a pawl *m'* to prevent backward movement of said roller.

15. The chains *L* and *L* furnish a strong connection between the rear axle *A* and platform *K*; but for additional security I employ a number of guard-chains, two of which *N* and *N* are connected with and extend diagonally between the front side of said axle and the central portion of said platform. Two others *N* and *N* in like manner extend between the rear side of said axle and the rear end of said platform, while two other chains *O* and *O* extend between and are connected with the latter and the front and rear ends of the saddle *F*.

20. The apparatus is now ready for use as follows, viz: The rear axle or truck is disconnected from the platform and moved close to the tree which is to be transplanted and the saddle turned upward against the same and securely fastened thereto by straps, ropes, chains, or in any desired manner, after which the roots of the tree are loosened, and said tree 25 by means of a suitable tackle is drawn over until its weight is supported by said truck. The platform being now placed beneath the rear axle, and connected therewith by means of the windlass-chains, is raised until it supports the roots of the tree and the guard-chains then 30 connected. When a tree has been thus suspended, it may be readily and safely moved to the place where it is to be reset, when by reversing the removing operation said tree 35 may be placed in position and held until its roots are covered with soil, the entire proceedings being carried on without the difficulties and dangers that usually attend the transplanting of trees which have attained any 40 considerable size.

50. In order that a tree may be more securely held in lateral position upon the saddle, a number of sharp metal studs *f* and *f'* are preferably caused to project upward from the latter at points near its ends, which studs engage with the bark of the tree and operate to insure its position. To facilitate the securing of said saddle to the trunk of a tree, there is prefer-

ably a number of studs *f* and *f'* secured within and caused to project laterally from the side edges of the same, which studs serve as supports for the feet of the operator and enable him to readily climb to the top of said saddle when the same occupies a vertical position.

Having thus described my invention, what I claim is—

1. In a tree-transplanting apparatus, the combination of a wheeled truck, a vertically-adjustable bolster, and a saddle which is secured to the upper side of such bolster and is adapted to receive and sustain the trunk of a tree, substantially as and for the purpose specified.

2. In combination with the axle of the rear truck, the bolster adapted to be moved vertically thereon, the pins which operate to lock the bolster in position, and the springs that act to counterbalance the weight of said bolster, substantially as and for the purpose shown.

3. In combination with the rear truck, which is adapted to support a tree in an inclined position, the platform that is pivotally connected with the front truck and is connected with the rear truck by chains which may be operated to raise said platform into contact with the roots of the tree, substantially as and for the purpose set forth.

4. As a means for connecting the rear truck with the platform, and in combination therewith, chains which are each at one end fastened to said platform, and windlass-spools that are journaled upon the axle of said truck and each adapted to receive and wind the upper end of one of said chains, substantially as and for the purpose shown and described.

5. In combination with the rear truck, the platform, the chains and windlass used for connecting the same together, and guard-chains which are attached to and extend between said truck and platform, substantially as and for the purpose specified.

6. The tree-transplanting apparatus in which is combined the front and rear trucks, the connecting-platform, and the mechanism for adjusting the rear end of such platform, substantially as and for the purpose shown.

In testimony that I claim the foregoing I have hereunto set my hand this 4th day of June, A. D. 1889.

WILLIAM AUSTIN ESTES.
